Inventor,
Charles C. Griswold,
per Gridley & Co.,
his Attorneys,

UNITED STATES PATENT OFFICE.

CHARLES C. GRISWOLD, OF CHICAGO, ILLINOIS.

FIRE-ESCAPE.

SPECIFICATION forming part of Letters Patent No. 279,150, dated June 12, 1883.

Application filed March 13, 1883. (No model.)

To all whom it may concern:

Be it known that I, CHARLES C. GRISWOLD, of Chicago, in the county of Cook and State of Illinois, a citizen of the United States of America, have invented certain new and useful Improvements in Fire-Escapes, of which the following, in connection with the accompanying drawings, is a specification.

In the drawings, Figure 1 is a side elevation 10 of a building provided with fire-escapes embodying my invention. Fig. 2 is a detail, being a top view of the ladder support or bracket. Fig. 3 is a detail showing the front of the bracket and of a ladder arranged and supported 15 therein, and Fig. 4 is a detail in perspective of the upper part of one of the ladders.

Like letters of reference indicate like parts. A represents a building.

B B are ladder supports or brackets applied 20 permanently to the building, and arranged one above the other between the windows, being, by preference, between the vertical rows of windows, and each bracket being at about the height of the upper end of the lower sash, respectively, as shown. These brackets have a 25 front bar, a, supported by means of arms a' a', permanently applied to the building. In the example shown the arms a' a' consist of rods or bars of iron either laid with the wall while 30 the building is being erected or thereafter driven firmly therein. The arms a' a' project horizontally from the building, and are in the same plane. The bars a a are also made of metal, and are rigidly secured to the arms a' a', extending horizontally from one to the other, as 35 shown. It is not essential to this invention that the mode of applying the brackets to the building and of securing the bar a to the arms a' a' should be practiced precisely as shown and 40 described; nor is it absolutely essential, though preferable, that the brackets should be made of metal. By making them of metal they will be fire-proof, or practically so. The bar a has U-shaped parts B' B' extending inward or toward 45 the building, and C C are locks or catches pivoted to the inner side of the bar a, and capable of being moved or swung in the directions indicated by the arrows shown in Fig. 3. These locks perform the function of temporarily closing 50 the otherwise open ends of the parts B' B', as will hereinafter more fully appear.

D D are ladders, commonly known as "S-ladders." These ladders have side bars, the upper ends of which are hook-shaped, as shown. The ladders D D are of such a width that their 55 hooks may be hooked with facility upon the cross-bar of the U-shaped parts B' B'.

To apply my invention to use for the purpose for which it is intended I proceed as follows: The brackets B B, I apply to the building in the manner shown and described, the locks or catches C C being turned over toward each other in the manner indicated by the dotted or broken lines in Fig. 3, when they will support each other horizontally, their free 65 ends meeting each other as a horizontal position is reached. I then suspend the ladders on the brackets, beginning either at the upper or at the lower bracket. In beginning at the upper bracket the ladder first hung is taken 70 out at the upper story of the building, where it may be hung with facility. After hanging this ladder upon its supporting bracket I throw the locks C C over toward the ends of the bracket, as is plainly indicated by the full 75 lines in Fig. 3, thus preventing the ladder from being accidentally removed or disconnected from its support. I then hang the other ladders in like manner, moving out the lower end of each upper ladder, so as to permit the next 80 lower ladder to be properly suspended. The ladders after being once hung may be allowed to remain suspended for use as occasion may require; or they may be taken down after such an occasion has passed and stored in the building 85 for subsequent use. In beginning at the lower bracket, I hang and secure a ladder thereon, then take a second ladder and carry it up the one first hung, and suspend the second ladder in like manner from the second bracket, and 90 so on until the upper bracket is reached. In practice, however, I would deem it best merely to apply the brackets properly to the building and to supply the fire-department with the ladders, so that in case the building takes fire the 95 firemen may apply the ladders thereto, beginning at the lower bracket in the manner described. By this means the ladders may be applied very quickly, one fireman following the other each with a ladder.

It will be perceived that the fire-departments can carry and more easily manage a number

of comparatively short ladders than one which is extremely long and adapted to reach to the upper story of a very high building. It will also be perceived that both the brackets and 5 the ladders are easily accessible from the windows of the building, and that the necessity of providing stand-pipes with permanent rungs is avoided.

Having thus described my invention, what 10 I claim as new, and desire to secure by Letters Patent, is—

The combination, in a fire-escape, of a series of ladders, D D, having hook-shaped upper ends, and ladder-supporting bars having U-shaped parts B' B', and provided with the pivoted or swinging catches or locks C C, substantially as and for the purposes specified. 15

CHARLES C. GRISWOLD.
